Ms. 156

William A. Shaw of the County of Suffolk, Massachusetts, Letters Patent No 256 dated Dec 18th 1849.

The schedule referred to in these Letters Patent and making part of the same
of all persons to whom these presents shall come.

Be it known that I

William T. Shaw of the County of Suffolk, and State of Mass., will have invented or produced a new and original design in alto-relievo, which design when cast or founded is to be used in the construction of girandoles or other ornamental articles; and I do hereby declare that the said design is represented in the accompanying drawings.

The design represents a gothic Chapel or church of which the front end and one side, a part of the roof, and more or less of the Pinnacles on the two sides are seen in perspective view, the whole being made to project either in laps or alto-relievo from a plane surface as seen in cross-section in Figure 3; Figure 1, being the front view or elevation. The production of the design, and the pattern for it, having cost me about fifty dollars. I am anxious to secure it, particularly so far as to prevent persons from taking a casting of it, as sold in the market, and仿制ing and using the same as a pattern to found others by.

In the said design a, a, a, are columns or buttresses for supporting pinnacles b, b, b. of the front end and one side c, c, c, are portions of the pinnacles of the opposite side seen above the roof d. The doors, windows, walls, and remaining parts of the figure or designs will be readily understood by inspection of the drawings.

I claim the said design or pattern or combination of ornamental parts composing

the same in their arrangement in belief and
above described and as exhibited in the draw-
ings.

In testimony whereof I have hereunto set my
signature this fourth day of December A.D. 1849

William F. Shaw
